CURT R. BURKHARDT, OF TEANECK, NEW JERSEY, ASSIGNOR OF ONE-HALF TO JOHN A. SCHARWATH, OF ELIZABETH, NEW JERSEY.

MOLD FOR CONCRETE SHINGLES.

1,291,394.

Specification of Letters Patent. Patented Jan. 14, 1919.

Application filed September 1, 1917. Serial No. 189,404. BEST AVAILABLE COPY

To all whom it may concern:

Be it known that I, CURT R. BURKHARDT, a citizen of the United States of America, and a resident of Teaneck, county of Bergen, and State of New Jersey, have invented certain new and useful Improvements in Molds for Concrete Shingles, of which the following is a specification, reference being had to the accompanying drawings, forming a part thereof.

My invention relates to the art of manufacturing concrete shingles and has special reference to molds adapted to be utilized in hydraulic or other presses for this purpose.

One object of my invention is to provide a simple mold structure that shall be reliable in operation and which shall embody means for avoiding distortion of the press heads or strains tending to distort them, due to the tapered form of the shingle, when the press is operated.

In order that my invention may be thoroughly understood, I will now proceed to describe the same in the following specification, and will then point out the novel features thereof in appended claims.

Referring to the drawings:

Figure 1 is a transverse sectional elevation taken on the line 1—1 of Fig. 3, and Fig. 2 is a sectional elevation at right angles to Fig. 1, and taken on the line 2—2 of Fig. 3.

Fig. 3 is a plan view of a mold which constitutes an embodiment of my invention.

Figs. 4 and 5 are perspective views of an asbestos cement shingle such as the mold of the previous figures is adapted to produce.

Referring to Figs. 1, 2 and 3 the structure here shown comprises a mold frame 10 having a flange or edge strip 11, a removable block 12 which is fitted loosely into the mold frame and has its bottom edges chamfered at 13 to receive the flange or edge strip of the frame.

The block 12 is further provided with recesses 14 in which springs 15 are disposed. Mounted on the block and resting on the springs 15 near one end is a mold plate 16.

As shown in Fig. 2, the mold is preferably divided into two parts by a partition 17 which is enlarged at the bottom to form ledges 18 corresponding to the flanges 11 on the sides. In the same way the block 12 is

preferably divided into two parts which are fitted into the mold on the respective sides of 55 the partition.

In fact, it is evident that the mold may either be arranged for one block and adapted to produce a single article at one operation, or it may be subdivided into a plurality of 60 sections by one or more partitions, and by utilizing blocks corresponding to the number of spaces.

Each mold block section has its upper edges cut back to form a space into which an 65 apron or flange 19 of the mold plate extends. The arrangement of parts is such that the flange at all times overhangs the edges of the mold block on which it is mounted, thereby preventing a plastic material from 70 working its way under the mold plate and between the plate and the block.

20 designates a stationary press head and 21 a movable press head. The press is not shown and may be formed in any suitable 75 manner and may for example be constructed as described in my copending application Serial No. 101,461 filed June 3, 1916.

The springs are relatively stiff and are fully expanded except at the final movement 80 of the press when they yield to permit the press head to move slightly farther and take up for the shrinkage of the thick part of the shingle after the thin part of the shingle is entirely solid and practically non-com- 85 pressible.

The mold plate is so formed that when the springs 15 are compressed and it rests on the block the space then existing between the mold plate and the stationary member of 90 the press, is such as to produce the desired shingle form. This as shown in Figs. 4 and 5, is preferably tapered from end to end, has edge notches 23, and cored recesses 24 to reduce the weight in the thicker part of the 95 shingle.

If a tapered mold plate is utilized without any springs as if, for example, the springs 15 were removed, and the mold filled and the press actuated, the strains due to the 100 reaction of the press, are not parallel to the direction of the press movement or, in other words, they are out of alignment with the press action and tend to produce strains in the press.

The operativeness of the structure illus-

trated has been demonstrated in practice and while I do not wish to be limited to any theory of operation, I now believe that the operation is correctly outlined as follows:—

Assuming first that the opposed press head surfaces are parallel and normal to the action of the press, the mold plate which determines the form of the shingle if solidly mounted on the base of the mold, provides a tapered mold space which is filled with a soft mixture of cement and asbestos fibers. This soft mass contains a great deal of water, the thicker part containing consequently more than the thinner part.

The press head against which the plastic mass is squeezed is maintained at a relatively high temperature in any suitable manner. Consequently when high pressure is exerted the water is first evaporated from the thinner part of the shingle and the shrinkage in this part is less than the shrinkage in the thick part. Consequently the thin part sets and becomes a practically non-compressible solid mass preventing further motion of the press head, whereas the thicker part requires a very slightly farther motion of the members in order to take up the additional shrinkage in this part of the shingle.

It is this difference in the distribution of water and the difference in shrinkage which is believed to put a strain on the press and the springs of my present invention are provided in such a way as to overcome the strains on the press by permitting a very slight compression of the spring under the thin end to allow the necessary additional

movement of the press to take up the shrinkage in the thick part of the shingle.

It is evident that my invention may be embodied in structures of various kinds and I intend that only such limitations be imposed as are indicated in the appended claims.

What I claim is:

1. A press mold comprising a mold frame adapted to fit against one of the heads of the press and having a movable block, a mold plate mounted on the block, and a spring between the mold plate and the block, offset from the center.

2. A press mold comprising a mold frame adapted to fit against one of the heads of the press and having a movable block, a mold plate mounted on the block and having a flange overhanging the edges thereof, and a spring for resiliently supporting one end of the mold plate.

3. A press mold comprising a parallel surface, a block adapted to be engaged by one of the press heads, a mold plate of tapered form mounted on the block and resilient means for elevating the thick end of the mold plate.

4. A press mold comprising a parallel surface, a block adapted to be engaged by one of the press heads, a mold plate of tapered form mounted on the block, and a spring for elevating the thick end of the mold plate to permit a slight additional movement of the press head after the thin part of the article being molded is set.

In witness whereof I have hereunto set my hand this 27th day of August, 1917.

CURT R. BURKHARDT.
